WILLIAM OTTO MICHELSSEN, OF WOODHAVEN, NEW YORK

INTERNAL-COMBUSTION ENGINE

Application filed February 20, 1929. Serial No. 341,480.

This invention relates to new and useful improvements in internal combustion engines, especially as used in automobile construction and in particular to facilitate their starting.

It is a known fact, that when starting an internal combustion engine while it is cold, by means of an electric motor that is supplied with electric current from a battery, which simultaneously is furnishing current for the ignition system of said engine, an arrangement that is generally embodied in the power plant of an automobile, that this battery is often overloaded by the heavy discharge that the starting motor imposes upon it. This heavy discharge is still further increased in cold weather when the oil in the engine is congealed and resists the efforts of the starting motor to a greater extent, effecting a considerable lowering of the voltage available for ignition of the engine. Frequently the gap formed between the spark plug electrodes, too wide for the purpose of starting the engine, causes failure to produce a spark until after the engine has been "turned over" a number of times and the resistance of the crank case oil has thereby been reduced. This is particularly true when the battery is not fully charged.

Furthermore, it is a known fact that when an engine is being started, the operating of the priming means, often referred to as the choke valve, results in a very rich mixture being transmitted into the engine cylinders, thereby greatly facilitating the starting of the engine.

It is, therefore, one of the objects of my invention to provide means for temporarily reducing the spark gaps in the several spark plugs of the engine and to simultaneously actuate the priming device whereby sparks will be insured and a rich mixture directed into the cylinders for ignition by said sparks.

This reduces the length of time that is necessary to apply the starting motor, and consequently preserves the battery.

Another object of the invention is a slight widening of the "working gap", as compared to the one generally employed in the ordinary

constant gap spark plug. This is permissible, because no allowance has to be made in determining this gap, for the overtaxed condition of the battery when starting the engine. The advantage gained is a larger spark, a consequent more instantaneous and more complete combustion, which results in more power. Also idling of the engine is improved since the larger spark is better able to ignite the small quantity of gas mixture that is allowed to enter the engine.

A still further object of the invention lies in the provision of a manually operable element by means of which the movable electrodes of the spark plugs will be actuated in unison and the priming means operated simultaneously with the actuation of said movable electrodes.

With these and other objects in view which will more fully appear, the nature of the invention will be more clearly understood by following the description, the appended claims, and the several views illustrated in the accompanying drawings.

In the drawings:

Figure 1 is a side elevation of an internal combustion engine showing the application of my invention,

Figure 2 is an enlarged plan view partly in section showing the manually operable element for simultaneously actuating the movable electrodes and the choke valve,

Figure 3 is an enlarged plan view of the engine without the contact manifold but showing the means for simultaneously actuating the movable electrodes in unison,

Figure 4 is an enlarged sectional view of one of the spark plugs showing an actuating arm connected to the movable electrode,

Figure 5 is an enlarged end elevation thereof showing the actuating arm, the actuating link connected thereto, and the conductor lead, and

Figure 6 is an enlarged elevation of the other end of the spark plug showing the normal position of the movable electrode in full lines and the adjusted position of said movable electrode in dotted lines.

Referring to the accompanying drawings, 100

I have illustrated an internal combustion engine A which includes the usual intake manifold A', the carburetor B having a normally open choke valve C, and a plurality of spark plugs D. The choke valve C is of the usual construction and includes a supporting shaft 5, an actuating rock arm 6, and a spring 7 which has one end connected to the arm 6 and the other end to the carburetor to yieldably retain the valve C in its open position. The spark plugs D are arranged in alignment and in a plane extending longitudinally of the engine.

Each spark plug includes the usual metallic conductor plug 8 in which an insulator 9 is centrally mounted in the usual manner. A fixed electrode 10 is secured to the inner end of the plug 8 and includes a stem which terminates in a laterally extending arm 11. The insulator 9 is provided with an axially disposed bore 12 which extends throughout the length of the insulator, and journaled in this bore is a movable electrode 13 which includes at the inner end of the plug a stem 14. This stem 14 terminates in a laterally extending arm 15 which is U-shaped in plan view as shown in Fig. 6. Thus, the arm 15 includes a curved outer face which is disposed eccentrically to the axis of the movable electrode. The arm 15 is disposed in the same plane as the arm 11 of the fixed electrode and the distance between the axis of the movable electrode 13 and the terminal end of the portion 15 is less than the distance between said axis and the terminal end of the arm 11. When the movable electrode is in its normal position, that is, in the full line position shown in Figure 6, a spark gap is provided between the terminal ends of the two electrodes which is of a predetermined size for use when the engine is warm. Usually this normal spark gap is .030 inch. When the movable electrode 13 is oscillated to the dotted line position shown in Figure 6, the spark gap will be gradually reduced by reason of the eccentric shape of the contact arm 15, until the spark gap is about .015 inch in width.

In order to simultaneously actuate the movable electrodes of the several spark plugs in unison whereby all of the spark gaps will be varied, I have fixed on actuating arm 16 to each movable electrode 13 for oscillating said electrode in the bore 12. Each electrode 13 is held against longitudinal movement relative to the insulator 9 by reason of a flange 17 formed on the inner end of the electrode and cooperating with a seat formed in the insulator, and by a plurality of clamping nuts 18 which are threaded onto the outer end of said electrode 13. A gasket 17' is placed between flange 17 and the seat formed in the insulator, to insure a compression tight joint. A spring washer 18' acts to compensate for wear of gasket 17'. A sleeve 19 is loosely fit-

ted over electrode 13, permitting same to rotate. It is equipped with a groove 19^a to receive the clip 20 of the conductor lead 21. As an alternative the nut 19^b is threaded on the shoulder of the sleeve 19 to clamp therebetween the clip 20, if so desired. The actuating arms 16 extend from the respective plugs in the same general direction and are connected to a single actuating link 22 through the medium of pin and slot connections 23. A coil spring 24 is connected at one end to the link 22 and at its other end to an upstanding ear 25 formed on a bracket 26 which is bolted to the head 27 of the engine. The spring 24 functions to yieldably retain the movable electrodes in their normal positions with the maximum gaps between the electrodes. It will be observed that upon a pull on the link 22 in a direction against the tension of the spring 24, all of the actuating arms 16 will be operated simultaneously and the movable electrodes 13 will be oscillated so as to simultaneously and uniformly decrease the sizes of the spark gaps in the several plugs.

It is a known fact that when starting an internal combustion engine while it is cold, the battery is overtaxed and this is particularly true when the battery charge is below normal. Under these conditions, it is necessary to actuate the priming means so as to supply the engine with a very rich mixture, and also desirable to reduce the size of the spark gap in order to insure sparks in the spark plugs.

In order to close the choke valve C and to simultaneously actuate the movable electrodes to reduce the spark gaps, I have provided a manually operable element E which is mounted on the dash X of the motor vehicle. This mounting includes a sleeve 28 which is clamped to the dash. An extension tube 29 is fixedly located within the sleeve 28, and a stem 30 which is fixed to the manually operable element E, is slidably mounted within the tube 29. A U-shaped bracket 31 has one of its legs 32 clamped to the tube 29. A Bowden wire 33, or other connection, has one end slidably mounted in the other leg 34 of the bracket 31 and this end is rigidly connected to a cross-head 35 which is mounted on a screw 36 having threaded adjustable engagement with the stem 30. The other end of the wire 33 is connected to the actuating arm 6 of the choke valve C. A second Bowden wire 37 has one end slidably mounted in the leg 34 of the bracket 31 and is fixedly connected to the cross-head 35, the other end of the wire 37 being connected to the actuating link 22.

In operation, assuming the engine to be cold, the operator pulls on the manually operable hand piece E and consequently the choke valve C is closed and the spark gaps are reduced. After the engine has started,

the operator gradually returns the hand piece E as the engine warms-up and the springs 7 and 24 respectively return the choke valve C to its normal open position and the movable electrodes to their normal or side gap positions.

In order to limit the extreme positions of the movable electrodes, I have provided the bracket 26 with spaced posts 38 and 39 which form stops for cooperation with one of the actuating arms 16.

I claim:

1. The combination of an internal combustion engine including a plurality of cylinders, a spark plug associated with each cylinder, each plug including two electrodes one being movable relative to the other to vary the spark gap therebetween, and an intake manifold, a carburetor including a normally inoperative priming device, and means for operating the priming device and for simultaneously actuating the movable electrodes in unison and in a direction to decrease the spark gaps of the several plugs.
2. The combination of an internal combustion engine including a plurality of cylinders, a spark plug associated with each cylinder, each plug including two electrodes one being movable relative to the other to vary the spark gap therebetween, and an intake manifold, a carburetor including a normally inoperative priming device, and operating means including a manually operable element for operating the priming device and for simultaneously actuating the movable electrodes in unison and in a direction to decrease the spark gaps of the several plugs.

3. The combination of an internal combustion engine including a plurality of cylinders, a spark plug associated with each cylinder, each plug including two electrodes one being movable relative to the other to vary the spark gap therebetween, and an intake manifold, a carburetor including a normally inoperative priming device, and operating means for operating the priming device and for simultaneously actuating the movable electrodes in unison and in a direction to decrease the spark gaps of the several plugs, said means including a single operating element, a connection between said element and the priming device, and another connection between the element and the movable electrodes.

4. The combination of an internal combustion engine including a plurality of cylinders, a spark plug associated with each cylinder, each plug including two electrodes one being movable relative to the other to vary the spark gap therebetween, an intake manifold, a carburetor including a normally inoperative priming device, yieldable means normally holding the movable electrodes in position relative to the associated electrodes with maximum gaps therebetween, and

yieldable means for normally holding the priming device in its inoperative position, and a manually operable element for operating the priming device against the tension of its holding means and for simultaneously actuating the movable electrodes in unison against the tension of their yieldable means and in a direction to decrease the spark gaps of the several plugs.

5. The combination of an internal combustion engine including a plurality of cylinders, a spark plug associated with each cylinder, each plug including two electrodes one being movable relative to the other to vary the spark gap therebetween, and an intake manifold, a carburetor including a normally inoperative priming device, means for operating the priming device and for simultaneously actuating the movable electrodes in unison and in a direction to decrease the spark gaps of the several plugs, and means for limiting the movement of the operating means.

In testimony whereof, I have hereunto subscribed my name.

WILLIAM OTTO MICHELSSEN.
